UNITED STATES PATENT OFFICE.

ANTONIO GUERRIERO, OF BROOKLYN, NEW YORK.

DESIGN FOR AN AUTOMOBILE-FENDER.

51,414.

Specification for Design.

Patented Oct. 23, 1917.

Application filed August 1, 1916. Serial No. 112,621. Term of patent 7 years.

To all whom it may concern:

Be it known that I, ANTONIO GUERRIERO, a subject of the King of Italy, residing at Brooklyn, in the county of Kings and State of New York, have invented a new, original, and ornamental Design for Automobile-Fenders, of which the following is a specification, reference being had to the accompanying drawing, forming part thereof, in which—

Figure 1. is a perspective view, and Fig. 2. an end elevation of an automobile fender, showing my new design.

I claim:

The ornamental design for an automobile fender, as shown.

ANTONIO GUERRIERO.
